CRYSTAL CONTROLLED OSCILLATOR
CIRCUIT

Hallan E. Goldstine and James W. Conklin, Rocky Point, N. Y., assignors to Radio Corporation of America, a corporation of Delaware

Application March 9, 1932, Serial No. 597,740

3 Claims. (Cl. 250—36)

Professor Cady has described in connection with Figure 3 of his United States Patent 1,472,583, an efficient crystal controlled oscillator. This oscillator makes use of a crystal and a 5 parallel tuned circuit in the grid circuit of an electron discharge device which is set into oscillation partly due to regenerative interelement feed back of the device, and partly due to regenerative inductive feed back by means of a tickler coil, to the parallel tuned input circuit.

However, due to the fact that the capacitive reactance of the crystal holder at resonance is equal in magnitude to the resistance of the crystal, but 90 degrees away from or in quadrature therewith, it is apparent that even with the 15 crystal controlling the voltages generated, the resonance curve of the oscillator as a whole is not as sharp as it could be. Accordingly, to sharpen the resonance curve of the oscillator and 20 cause controlling grid voltages to be applied to the grid at correct phase for only oscillation generation at the desired frequency, is the principal object of our present invention. To do so, we provide an arrangement whereby the reactance 25 of the crystal holder is rendered ineffective for altering the phase of voltages applied to the control grid of the electron discharge device. Not only does this arrangement sharpen the frequency 30 characteristic of the oscillating system as a whole, but, it will be found that even with relatively heavy loads on the crystal oscillator, the output need not be lowered to insure frequency stability as would be the case without our present invention.

35 Our present invention is described more fully with the aid of the accompanying drawing, wherein, as illustrated diagrammatically in Figures 1, 2, 3 and 4, preferred embodiments and in wiring diagram form of our improved crystal controlled oscillating systems are shown.

Between the control grid 2 and cathode 4, shown in Figure 1 as of the A. C. heated type and in Figure 2 as of the indirectly heated type, although any other type may be used, there is 45 shown an electromechanical vibrator or piezo-electric crystal controlling element 6. Also, between the grid 2 and filament 4 there is connected the parallel tuned circuit 8 comprising an inductance coil 10 shunted by a variable tuning condenser 12. Some intermediate point along the inductance or reactance 10 is connected through return lead 12 to the filament or ground. The upper end of the parallel tuned circuit 8 is connected to one electrode of piezo-electric 55 crystal 6 and the other side of the parallel tuned

circuit is connected through neutralizing condenser 14 to another electrode of piezo-electric crystal 6. By variation of condenser 14 the capacity formed by the electrodes of piezo-electric crystal 6 may be neutralized, preferably completely, or to any desired extent.

We prefer, however, that the circuit be made slightly degenerative, thereby neutralizing any extraneous capacities and over compensating for any chance of the circuit oscillating. By having a 10 degenerative feedback, the output will not be lowered due to the degeneration because the low series impedance of the crystal will cause the circuit to oscillate practically as strong at the fundamental crystal frequency.

5 Inductance feed back from the plate 16 is accomplished through tickler coil or feed back coil 18 grounded for high frequency currents at its potential supply end 20 through the action of blocking or by-passing condenser 22, electrostatic shielding 24 is provided between the coils 18, 10 to prevent to any desired degree capacitive coupling therebetween. Output energy is derived through blocking condenser 26 through the leads indicated "output" on the 15 drawing.

For establishing a suitable bias on control grid 2, resistor 28 is provided and is preferably of high ohmic value.

At resonance, the capacitance of the crystal 30 and its associated electrodes has a value in impedance equal to the resistance of the resonator at the desired frequency. Consequently, it will be obvious that at the desired frequency the phase of voltages applied to the grid and plate 35 will not be exactly that required for best operation at the natural frequency of the crystal. Accordingly, by adjustment of condenser 14 until the capacitive reactance of the crystal and its associated electrodes are eliminated or effectively neutralized or compensated, the circuit 40 will oscillate at a frequency corresponding almost exactly with that frequency for which the crystal is ground. In addition, as already pointed out, variations in load will produce no effective 45 reaction back upon the crystal as a result of which relatively large stable outputs may be derived from the present system.

As a further improvement, there may be provided in shunt with the grid leak resistor 28, a 50 low impedance, connected across the grid 2-filament 4 circuit in the form of a resistance 30 in series with a by-passing condenser 32. Resistance 30 is of relatively low value, and, prevents the generation of spurious oscillations through 55

its by-passing effect. However, oscillations of desired frequency are built up in the parallel tuned circuit 8 by virtue of the lower impedance to the desired frequency offered by crystal 6, as a result of which in the output circuit of the system, only energy of desired frequency, namely that of the crystal, appears. This action is more fully described in the copending applications of C. W. Hansell and Harold O. Peterson, Serial #598,566 and 596,197, respectively, filed March 14, 1932 and March 2, 1932, respectively, wherein it has been shown also that the resistance 30 may be replaced by a choke coil, or, merely by a condenser of suitable value.

15 In the arrangement shown in Figure 2, the parallel tuned circuit 8 has been replaced by an inductive reactance or coil 10 shunted by two serially connected condensers 13, 15. The return lead 12 is connected to a point intermediate the condensers 13, 15 rather than to some intermediate point on the reactance or coil 10. The neutralizing condenser 14 is connected in a similar fashion as that given in Figure 1 and in general the operation of both schemes are identical.

20 However, in the arrangement shown in Figure 2, neutralizing condenser 14 may be dispensed with, the neutralizing connection being made to some intermediate point on the grid tuning condenser. Further, if desired, condensers 13, 15 are made independently variable, rather than of the unicontrol variety.

25 In addition, in the arrangement shown in Figure 2, a screen grid tube has been illustrated having a screen grid 40 suitably grounded for high frequency currents by the action of by-passing condenser 42. In this manner also, undesired interelement feed back is prevented as a result of which tendency towards spurious or parasitic oscillation generation is still further prevented.

30 If desired, the neutralizing circuit may be inductively coupled to either the plate circuit or grid circuit as shown diagrammatically in Figures 3 and 4. In Figure 3, desired neutralization is accomplished by coupling coil 50 to the plate coil 18; and, in Figure 4 it is accomplished by coupling coil 50 to the grid inductance coil 10.

35 Having thus described our invention, what we claim is:

40 1. A constant frequency oscillator comprising a tube having an anode, a cathode, and a grid, a parallel tuned circuit having a coil and a con-

denser, a two electrode piezo-electric crystal, a connection from one terminal of said crystal to one end of said tuned circuit, a connection from the other terminal of said crystal to said grid, a connection from an intermediate point on said parallel tuned circuit to said cathode, a neutralizing condenser, a connection from one terminal of said neutralizing condenser to said grid, a connection from the other terminal of said neutralizing condenser to the other end of said tuned circuit, and a feedback coil connected between said anode and cathode and coupled to the coil of said tuned circuit.

45 2. A constant frequency oscillation generator comprising a tube having an anode, a cathode and a grid, a tuned circuit comprising an inductance coil and a condenser connected in parallel, a piezo electric crystal having two electrodes, a connection from one of said crystal electrodes to said grid, a connection from the other of said crystal electrodes to one terminal of said parallel tuned circuit, a connection from a point intermediate the ends of said coil to said cathode, a neutralizing condenser, a connection from one terminal of said neutralizing condenser to said grid, a connection from the other terminal of said neutralizing condenser to the other terminal of said parallel tuned circuit, and a feedback coil connected between said anode and cathode and coupled to the coil of said parallel tuned circuit.

50 3. A constant frequency oscillation generator comprising a tube having an anode, a cathode, and a grid, an inductance coil, a pair of serially connected condensers connected in shunt to said inductance coil, said condensers and coil forming a parallel tuned circuit, a piezo-electric crystal having two electrodes, a connection from one of said crystal electrodes to said grid, a connection from the other of said crystal electrodes to one terminal of said parallel tuned circuit, a connection from a point between said serially connected condensers to said cathode, a neutralizing condenser, a connection from one terminal of said neutralizing condenser to said grid, a connection from the other terminal of said neutralizing condenser to the other terminal of said parallel tuned circuit, and a feedback coil connected between said anode and cathode and coupled to the coil of said parallel tuned circuit.
